G. M. TURNER

APPARATUS FOR SEPARATING GASOLINE FROM NATURAL GAS

Original Filed May 7, 1920

UNITED STATES PATENT OFFICE.

GEORGE M. TURNER, OF RIVERSIDE, CALIFORNIA.

APPARATUS FOR SEPARATING GASOLINE FROM NATURAL GAS.

Original application filed May 7, 1920, Serial No. 379,582. Divided and this application filed January 4, 1921. Serial No. 434,894.

To all whom it may concern:

Be it known that I, GEORGE M. TURNER, a citizen of the United States, residing at Riverside, in the county of Riverside and State of California, have invented certain new and useful Improvements in Apparatus for Separating Gasoline from Natural Gas, of which the following is a specification.

This invention relates to apparatus for the extraction of gasoline from gases and vapors, and particularly from natural gas, and pertains to the use of an absorbing oil or other absorbing material for extracting the gasoline content of gas.

One object of the invention is to provide an efficient and advantageous apparatus for effecting by the use of centrifugal means, the separation of the gasoline and the absorption of the same by an absorbing medium.

One feature of the invention provides for the thorough blending of the gasoline and gas with the absorbing oil, and includes the apparatus for conducting the continuous separation and absorption process described in my co-pending application Serial No. 379,582 filed May 7, 1920.

Details of these and other features provide for the use of centrifugal force for effecting quickly such thorough blending and provide details of construction of centrifugal apparatus whereby the blending process is conducted.

The present invention is to be differentiated from apparatus now in use which requires the use of relatively large absorbing surfaces, and the use of mineral seal oil and pressures ranging up to several hundred pounds. The present invention provides for the relatively rapid mixing of the absorbing liquid with the gaseous medium by the use of centrifugal force, which force also provides a very considerable portion of the necessary pressure.

The operation of the apparatus and the details of construction are explained in the following specification, claimed in the accompanying claims, and illustrated in the drawing which forms a part of this application.

Referring to the drawing, Figure 1 is a vertical section through the centrifugal blending apparatus,

Figure 2 is a sectional view, partly broken away, on the line 2--2 of Figure 1, looking down on the rotor member, and

Figure 3 is an exterior view with a portion of the casing broken away and illustrating the relative position of the interior parts of the apparatus.

Referring in detail to the constructions illustrated in the drawing, 1 is the main casing which is substantially circular horizontally. Extending through the center of the casing 1 and vertically, is a drive shaft 2 having at its lower end a fixed pulley 2^a which is driven by a belt 2^b from a source of motive power 2^c, which is illustrated as an electric motor. The shaft 2 is journaled in the casing 1 at the points 3, and is provided with suitable stuffing boxes or packing glands 4, which latter assist in preventing the escape of materials along the shaft 2. The lower end of the shaft rests on a suitable base 5 and roller or ball bearing means is provided for effecting the free movement of the shaft 2 at its lower end. The interior of the casing includes a rotor member 6 which is formed of a flat plate-like member having a substantially circular periphery and which is fixed to rotate with the shaft 2 by means of a key member 7. The hub portion of the member 6 rests on an annular collar 8 fixed to the shaft 2 and prevents the slipping of the rotor member 6 along the shaft. On the upper and under faces of the rotor member 6 are flange members 9 which extend radially and project substantially at right angles from the opposite faces of the member 6. These flanges 9 are secured to the rotor member by any suitable means, such as welding, as indicated at the point 10. The hub ends of the flanges 9 are secured to a perforate member 11 which encircles the shaft 2 and which likewise is rigidly secured to the rotor member. The outer ends of the flange members 9 are secured by the circular plate members 12, which are likewise fastened to the rotor member, and which are freely perforated with the openings 13. The flanges 9 on one side of the plate-member 6 are staggered with respect to those on the opposite side, and all the flanges are very rigidly secured by means of their fastenings to the members 11, 6 and 12. from the ends of the flange members 9 and beyond the member 12 are the radially extending agitating arms 14, which are rigidly secured for rotation with the rotor member 6 and the flanges 9. Positioned immediately at the periphery of the rotor member 6 and spaced from the inner wall of the casing 1 is a filter screen member 15 which closely embraces and encircles the periphery of the rotor member. Fixed baffles or agitating arms 16 are secured to the screen member 15 and are positioned in staggered relation with respect to the movable arms 14. Brace members 17 extend from the inner wall of the casing 1 and constitute fastening means and spacing means for securing the filter member 15 in fixed relation to the casing 1 and the rotor member.

Pipe means for the introduction of an absorbing liquid is indicated at 18, and a control valve for regulating the entry of this liquid is indicated at 18^a. Pressure means for the supply of oil is diagrammatically represented by the pump 18^b. Natural gas under pressure, or other gasoline, or kerosene containing gaseous or vaporous medium, is led into the casing through a pipe 19 having the control valve 19^a and a pressure pump 19^b. An outlet for the absorbent and gas is indicated by the pipe 20, which has a suitable control valve 20^a. A pressure gage is indicated at 21.

The operation of the apparatus will be understood from the following. Sufficient absorbent is admitted and the apparatus is started by turning on the motor 2^c and rotating the shaft 2 with its rotor member 6 and parts secured thereto. The action of these revolving parts generates considerable centrifugal force and throws the absorbing liquid, which may be mineral seal oil, or other satisfactory absorbing medium, toward the outer wall of the casing 1. As the absorbing liquid is admitted, this centrifugal force will bank up the oil filling the space between the casing 1 and eventually covering the periphery of the rotor member 6. During this banking up process the liquid coming into contact with the agitating arms 14 and 16 is subjected to a very severe agitating treatment. Natural gas under pressure is forced in through the pipe 19, with sufficient pressure to overcome the centrifugal force acting on the liquid at the periphery of the rotor member, and with sufficient force to be bubbled through the filter member 15 in the lower half of the casing and to be forced back through the filter member on the upper side of the casing, and finally to escape out through the pipe 20. The entering pressure of the gas and absorbing liquid must exceed the centrifugal effect of rotation in order that the materials may flow from the outer portion of the casing axially toward the outlet pipe 20. The agitation provided

by the arms 14 and 16, and the rapidly revolving rotor member with its flanges 9, serves to thoroughly break up the oil and to mix the oil with bubbles of gas, and the liquid which eventually flows out of the pipe 20 carries with it these bubbles. The final governing control for the pressure is the valve 20^a, which may be set to vary the outflow of oil and gas. If this valve is wide open, there will be but little pressure within the apparatus, but on the other hand, if this valve is partly closed, the pressure within the apparatus is correspondingly built up. The agitation due to the centrifugal action, the force of the flanges 9, the agitating arms 14 and 16, and the screen 15 serves to break the gas bubbles to a relatively small size and promotes the absorption of the gas by the absorbing liquid.

The apparatus requires no heat and the absorption is conducted most advantageously if the conditions are maintained at a fairly low temperature, the absorption of the gas by the absorbing liquid being correspondingly promoted.

After the absorption of the gasoline content of the gas by the absorbing oil the material may be subjected to the usual separation processes, such as distillation, for removing the gasoline from the absorbing oil. It is believed that the use of this centrifugal apparatus and the process thereof, will provide effective means of treating gasoline-carrying gases and vapors with an absorbing oil much more quickly, and to far better advantage than has heretofore been possible.

What I claim is:—

1. Apparatus for using absorbing oil to extract gasoline from natural gas, which apparatus comprises a closed casing, a rotor member mounted for rotation on an axis within said casing and arranged to move liquid oil and throw it centrifugally and having its peripheral edge spaced from the wall of said casing, said casing having a continuous imperforate wall encircling the periphery of said rotor member, first pipe means communicating with one side of said casing for the introduction of absorbing oil and gaseous material to be treated, and second pipe means for the removal of materials treated, said first and said second pipe means being on opposite sides axially of said rotor member, said apparatus constituting means for causing oil to collect as a bank of oil at the periphery of said rotor member due to the centrifugal action provided by said rotor member and to close the space between the periphery of the rotor member and the encircling casing wall, the sole path of communication between said first and said second pipe means being radially on one side of and to the periphery of said rotor member and through the

bank of oil about the periphery and thence to the opposite side and radially and centrally thereof.

2. Apparatus for using absorbing oil to extract gasoline from natural gas, which apparatus comprises a closed casing having a cylindrical wall and end walls therefor, a rotor member mounted for rotation on an axis within said casing and arranged to move oil and throw it centrifugally and having its peripheral edge spaced from the cylindrical wall of said casing, said cylindrical wall being imperforate and encircling the periphery of said rotor member, a perforate screen member encircling said rotor periphery and spaced from said cylindrical wall and extending from one end wall to the other, first pipe means communicating with one side of said casing for the introduction of absorbing oil and gaseous material to be treated, and second pipe means for the removal of materials treated, said first and said second pipe means being on opposite sides axially of said rotor member, said apparatus constituting means for causing oil to collect as a bank of oil at the periphery of said rotor member due to the centrifugal action provided by said rotor member and to close the space between the periphery of the rotor member and the encircling casing wall, the sole path of communication between said first and said second pipe means being radially on one side of and to the periphery of said rotor member, and through the bank of oil about the periphery and thence to the opposite side and radially and centrally thereof.

3. Apparatus for using absorbing oil to extract gasoline from natural gas, which apparatus comprises a casing, a rotor member mounted for rotation on an axis within said casing and having a substantially circular periphery spaced from the wall of said casing, said casing having a continuous imperforate wall encircling the periphery of said rotor member, radially extending agitating arms mounted on said rotor member and projecting beyond the periphery thereof, and arranged to move in a pool of oil and to throw the oil centrifugally, first pipe means communicating with one side of said casing for the introduction of absorbing oil and gaseous material to be treated, and second pipe means for the removal of materials treated, said first and said second pipe means being on opposite sides axially of said rotor member, said apparatus constituting means for causing oil to collect as a bank of oil at the periphery of said rotor member due to the centrifugal action provided by said rotor member and to close the space between the periphery of the rotor member and the encircling casing wall, the sole path of communication between said first and said sec-

ond pipe means being radially on one side of and to the periphery of said rotor member, and through the bank of oil about the periphery and thence to the opposite side and radially and centrally thereof.

4. Apparatus for using absorbing liquids to extract casing head gasoline from natural gas, which apparatus comprises a casing, a rotor member mounted for rotation on an axis within said casing and arranged to move in liquid material and throw it centrifugally and having a substantially circular periphery spaced from the wall of said casing, and radially extending agitating arms fixed with respect to said casing and spaced from said rotor member, said casing having a first opening for the introduction of absorbing liquid and gas to be treated, and a second opening for the removal of materials treated, said first opening and said second opening being substantially on opposite sides axially of said rotor member, said apparatus constituting means for causing liquid to collect at the periphery of said rotor member due to the centrifugal action provided by said rotor member, said radially extending arms lying in the sole path of communication between said first and said second openings.

5. Apparatus for using absorbing liquids to extract casing head gasoline from natural gas, which apparatus comprises a casing, a rotor member mounted for rotation on an axis within said casing and arranged to move in liquid material and throw it centrifugally and having an outer edge spaced from the wall of said casing, a first set of radially extending agitating arms fixed with respect to said casing and spaced from said rotor member, and a second set of radially extending agitating arms mounted on said rotor member and projecting beyond the periphery thereof for engaging liquid and throwing it centrifugally, said casing having a first opening for the introduction of absorbing liquid and gas to be treated and separate means for the removal of material treated, said first opening and said separate means being substantially on opposite sides axially of said rotor member, said apparatus constituting means for causing liquid to collect at the periphery of said rotor member due to the centrifugal action provided by said rotor member, said first set and said second set of arms lying in the sole path of communication between said first opening and said separate means.

6. Apparatus for using absorbing liquids to extract casing head gasoline from natural gas, which apparatus comprises a casing having opposite end walls and a side wall, a rotor member mounted for rotation on an axis within said casing and arranged to move in liquid material and throw it centrifugally and having a circular periphery

spaced from the side wall of said casing, a 5
perforate screen member closely encircling
said periphery and spaced from the inner
side wall of said casing and extending from
one end wall to the opposite end wall, radially
extending arms mounted on said rotor
member and projecting toward the periphery
thereof, and a second set of radially ex- 10
tending arms mounted on said screen mem-
ber and in staggered position with respect
to said arms on said rotor member, said
screen member extending across the sole
path of communication from the inlet end
to the outlet end and between said opposite
end walls. 15

7. Apparatus for using absorbing liquids
to extract casing head gasoline from natural
gas, which comprises a casing, a rotor mem-
ber mounted for rotation on an axis within
20 said casing and arranged to move in liquid
material and throw it centrifugally and hav-
ing a circular periphery spaced from the
walls of said casing, said rotor member con-
sisting of a plate-like member fixed for ro-
25 tation with an axial drive shaft, and flanges
on both sides of said rotor member projecting
from said rotor member axially and ex-
tending from the axis toward the periphery
of said rotor member for engaging liquid
30 and throwing it centrifugally, the flanges
on one side of said rotor member being
staggered with respect to those on the oppo-
site side thereof, said casing having first
means for the introduction of materials to
35 be treated and also separate means for the
removal of materials treated, said first means
and said separate means being on opposite
sides axially of said rotor member, said ap-
paratus constituting means for causing
40 liquid to collect at the periphery of said
rotor member due to the centrifugal action

provided by said rotor member, the sole
path of communication between said first
means and said separate means being radially
on one side of and to the periphery of 45
said rotor member, thence to the opposite
side and radially and centrally thereof.

8. Apparatus for using absorbing liquids
to extract casing head gasoline from natural
gas, which apparatus comprises a casing 50
having a wall extending substantially ver-
tically, means for supplying gas and ab-
sorbing liquids to the interior of said casing,
means for withdrawing materials treated,
and means for forming and maintaining by 55
centrifugal force a bank of liquid around
the wall of said casing, the sole path of com-
munication between said means for supply-
ing materials and said means for withdraw-
ing materials passing through the bank of 60
liquid.

9. Apparatus for using absorbing liquids
to extract casing head gasoline from natural
gas, which apparatus comprises a casing
having a wall extending vertically, means 65
for supplying gas and absorbing liquids to
the interior of said casing, means for with-
drawing materials treated, a rotor member
within said casing mounted to rotate on its
vertical axis in a horizontal plane, said 70
means for withdrawing materials leading
from a point positioned above said rotor
member, and power means associated with
said rotor member, said power means and
rotor member together comprising means 75
for forming and maintaining by centrifugal
force a bank of liquid around the wall of
said casing and having a thickness at least
as great as the distance from said wall to
said rotor member. 80

In testimony whereof I affix my signature.
GEORGE M. TURNER.
